COLLAR BLOCK FOR SHIRT PRESSES

William Colclough, Norwood, Ohio, assignor to
The American Laundry Machinery Company,
Norwood, Ohio, a corporation of Ohio

Application December 31, 1940, Serial No. 372,590

6 Claims. (Cl. 38—13)

This invention relates to improvements in a collar or neckband clamping mechanism for use in shirt pressing machines, the said mechanism being hereinafter termed a collar block.

In pressing men's shirts on modern laundry machinery it is customary to iron the collar or neckband portion in one of the preliminary operations, and to provide means for thereafter holding the collar in natural, finished shape while the shirt front is being ironed on a bosom press. A device of this nature which may be expanded to bear against the interior surface of the collar is preferably provided with clamping means for maintaining the collar portion in fixed position on the block. After the collar is ironed, by means and in a manner with which the present invention is not concerned, the operator arranges, or "dresses" the collar on the block, fixes it in place by a clamp or otherwise, and proceeds with the pressing operation on the shirt bosom. It is quite desirable that the expanding and clamping effect of the collar block be sufficiently positive to be effective and yet simple enough for rapid and convenient operation.

One object of the present invention is to provide an improved collar block, the operative mechanism therefor being self-contained.

A further object of the invention is to provide an improved collar block, the expander portion of which remains in operative, extended position only when the clamp is engaged.

A further object of the invention is to provide an improved collar block, the expander portion of which is slidably adjustable, and is maintained in desired position while the clamp is engaged, but which automatically returns to retracted, idle position when the clamp is disengaged.

These and other objects and advantages will be more clearly understood from the following description and the attached drawing illustrating a preferred embodiment in which:

Fig. 1 is a plan view of the collar block.

Fig. 2 is a section taken on the line 2—2 of Fig. 1.

Fig. 3 is a front elevation of the collar block.

Fig. 4 is a section taken on the line 4—4 of Fig. 3, the collar clamp being shown in released position.

The collar block shown in the drawing comprises a stationary member 10 and an expander portion 11. A pair of rods 12 and 12a are integrally secured to said expander portion and are fitted to slide freely in openings 13 in mem-

ber 10. A coil spring 14 connects expander 11 and stationary member 10 and tends to bias the expander into retracted position. The main section of the collar block is provided with several vertically bored apertures 15 which permit the block to be slidably fitted over pins 16 extending upwardly from the ironing table of the bosom press, shown in broken line outline in Fig. 2. The collar block is thereby readily removable from or replaceable on the table. The main section 10 is provided with two upwardly extending brackets 17 which carry, toward their rear edge, slots 18. A shaft 19 has its ends seated in said slots. A bell crank lever 20 is pivotally mounted on shaft 19.

A generally vertically positioned clamp member frequently termed a transom clamp 21 is bored or slotted, at 22, slightly over size with respect to one of the rods 12 which passes therethrough. The lower edge of member 21 is fitted in a slot 23 in the main portion 10. The clearance between rod 12 and transom clamp 21 is such that when the clamp is in substantially vertical position, as shown in Fig. 4, the expander 11 may be freely moved outwardly by manual pressure counter to the tension of spring 14, but when the transom clamp is moved out of vertical or inoperative position, as shown in Fig. 2, the upper and lower edges of the aperture 22 bind against the rod 12 with sufficient force to hold the rod against the retractive tendency of spring 14. As a result, when the clamp 21 is in the position shown in Fig. 2, the operator may move the expander rearwardly, by pressure of the hand against the button 24 which is affixed to the expander 11 by screws 25. The expander will remain in any present position within the limits of its travel until such subsequent time as the transom clamp is swung to vertical position in a manner now to be described.

A collar clamp 26 is pivotally mounted on pins 27 carried on brackets 17. A rearwardly extending arm 28 of clamp 26 abuts a forwardly extending arm 29 of bell crank lever 20 when the collar clamp is swung from the closed position of Fig. 2 to the open position of Fig. 4. The clockwise movement of bell crank arm 29, under the influence of the aforescribed swing of arm 28 of the collar clamp, causes the other bell crank arm 30 to abut the upper, inner face of transom clamp 21, thereby swinging the transom clamp on its pivoting edge 31 against the biasing tendency of spring 32, one end of which is affixed to the upper edge portion of transom clamp 21 and the other end to the main portion of the

collar block. Spring 32 therefore biases the transom clamp 21 to the clamping position whenever the collar clamp 26 is in the closed position shown in Fig. 2. When, however, the collar clamp 26 is swung to the open position of Fig. 4 by manual pressure against its upstanding wing portion 33, the operative relationship between collar clamp arm 28, bell crank lever arms 29 and 30, and transom clamp 21, effects the above described change of position of the transom clamp from the slanting position of Fig. 2 to the vertical position of Fig. 4 thereby releasing expander 11 so that spring 14 may retract the expander to its fully withdrawn position. Clockwise movement of bell crank arm 29 is limited by a stop 40 integral with bracket 17.

One end of a coil spring 34 is attached to collar clamp 26, at 35, and the other end to shaft 19. Since pivotal motion of collar clamp 26 from the open position of Fig. 4 to the closed position of Fig. 2, causes the spring 34 to snap from above center to below center with respect to the pivot point 27 of the collar clamp, the clamp is biased to either fully open or fully closed position and will remain in one or other said position until the status quo is manually disturbed.

The lower front face of the stationary main section 10 is provided with a sponge rubber cushion 36 against which the lower portion of the collar clamp abuts when the clamp is closed.

In actual use the device is operated as follows. The collar block is normally in inactive position with the expander fully retracted as shown in full line in Fig. 1 and the collar clamp is open as shown in Fig. 4. The block may, otherwise, be immediately brought to this inactive position by a simple opening movement of the collar clamp, which thereupon impinges on the arm 29 of the bell crank lever 20 so as to bring the other arm 30 of said bell crank to bear against the transom clamp and move it into a vertical position, thereby releasing the movable expander member. The operator then arranges the shirt on the buck in the ordinary way (the apparatus being conventional and not herein shown), and while doing so she dresses the collar, in upstanding position, around the collar block with the free ends of the neckband against the rubber cushion. She then flips over the collar clamp to the position shown in Fig. 2 so as to securely grip the free ends of the neckband, the points of the collar being arranged in upstanding position behind the wings 39 of the clamp 26. As hereinabove described this operation swings clamp extension 28 out of engagement with bell crank lever 29, which rotates counterclockwise to the position shown in Fig. 2 so as to permit spring 32 to draw transom clamp 21 into binding position on rod 12. The operator then moves the expander member outwardly towards the broken line position of Fig. 1 until the outer expander face 37 bears against the inner surface of the neckband. A yielding yet secure fit may be obtained by the use of an auxiliary spring member 38 mounted on the expander as shown in Fig. 2. The operator may then perform final dressing arrangement of the shirt on the ironing buck and proceed with the ironing operation.

Should the operator attempt to adjust the expander before closing clamp 26 the expander would merely return to retracted position when her hand is withdrawn, since the transom clamp is in inoperative position. When the ironing

operation has been completed, she flips clamp 26 to the open position shown in Fig. 4.

As previously explained, hereinabove, and as clearly shown in Fig. 4, this not only releases the free ends of the neckband portion but also permits the expander to withdraw to retracted position, freeing the collar portion, and the shirt may be removed from the buck in the usual way.

From the above description it is apparent that my improved collar block comprises a self-contained mechanism including a combined, interacting collar clamp and expander which may be economically constructed, yet is simply and readily operable even by a mechanically unskilled operator.

The transom clamp 21 which holds the expander member 11 while the collar clamp 26 is in operative position may of course be replaced by other clamping or holding devices familiar to those skilled in mechanical arts, provided there is an operative linkage between the expander holding device and the collar clamp permitting release of said expander holding device when the collar clamp is released.

What I claim is:

1. A collar block comprising a stationary member, an expander member slidably mounted for movement towards and away from said stationary member, and a collar clamp pivotally mounted on said stationary member, means engaging said expander for maintaining said expander in desired, spaced relationship to said stationary member, and means operatively associated with said collar clamp and said engaging means for maintaining said engagement only while said collar clamp is closed.

2. A collar block comprising a stationary member, an expander member slidably mounted for movement towards and away from said stationary member, and a collar clamp pivotally mounted on said stationary member, means engaging said expander in friction braking relationship for maintaining said expander in desired, spaced relationship to said stationary member, and means operatively associated with said collar clamp and said engaging means for terminating said friction braking relationship when said collar clamp is released.

3. A collar block comprising a stationary member, an expander member for to and fro movement with respect to said stationary member, and a collar clamp pivotally mounted on said stationary member, a transom clamp mounted on said stationary member and normally biased to frictional engagement with said expander, and means operatively associated with said collar clamp and disposed, by opening movement of said collar clamp, to trip said transom clamp and release said expander from said frictional engagement.

4. A collar block comprising a stationary member, an expander member slidably mounted for to and fro movement with respect to said stationary member, and a collar clamp pivotally mounted on said stationary member, spring means connecting said expander and said stationary member and normally tending to retract said expander towards said stationary member, clamping means engaging said expander and normally biased to maintain said expander in any set position counter to the tendency of said spring means, and means operatively associated with said collar clamp and disposed to

abut and release said expander clamping means when said collar clamp is opened, whereby said spring retracts said expander towards said stationary member.

5. A collar block comprising a stationary member, an expander member, and a collar clamp pivotally mounted on said stationary member, a pair of parallel rods carried by said expander member and slidably movable within a pair of bored apertures in said stationary member, a transom clamp comprising a plate having a perforated portion, one of said rods passing through said perforation and being slightly undersize with respect to said perforation, means mounted on said stationary member and abutting said transom clamp to move said transom clamp in and out of a plane perpendicular to said last mentioned rod so as to respectively clear said rod when the transom clamp is perpendicular as

aforesaid, but bind said rod when the transom clamp is moved from perpendicular position, and means operatively associated with said collar clamp and disposed to abut said first mentioned means so as to move said transom clamp to said perpendicular position only when said collar clamp is open.

10. An expandible collar block comprising a stationary member, a manually operatable, movable member biased to retracted position, holding means for said movable member having operative and inoperative positions, a manually operatable neckband clamp biased to either open or closed position, and actuating means between said clamp and said holding means and arranged, when said clamp is moved to open position, to move the holding means to inoperative position.

WILLIAM COLCLOUGH.
